Attorney.

UNITED STATES PATENT OFFICE

JOHN JACOB KAUFMANN, OF ELKINS PARK, PENNSYLVANIA, ASSIGNOR TO STEEL HEDDLE MANUFACTURING COMPANY, OF PHILADELPHIA, PENNSYLVANIA, A CORPORATION OF PENNSYLVANIA

HEDDLE FRAME

Application filed November 16, 1928. Serial No. 319,778.

My invention relates to heddle frames for looms, and it relates more particularly to that type of heddle frame in which individual warp controlling heddles are mounted on supporting bars carried by the frame.

The principal object of my present invention is to provide a heddle frame which will be simple and inexpensive to manufacture, yet quite durable, and which will be relatively light yet substantially rigid.

The nature and characteristic features of my invention will be more readily understood from the following description, taken in connection with the accompanying drawings forming part hereof, in which:

Figure 1 is a side elevation of a heddle frame embodying the main features of my present invention;

Fig. 2 is a fragmentary detail view enlarged, partly in section, of a corner portion of the heddle frame shown in Fig. 1, the same illustrating more clearly the construction and arrangement of the same;

Fig. 3 is an end elevation of the portion of the structure shown in Fig. 2; and

Fig. 4 is a vertical section, taken approximately on the line 4—4 of Fig. 2.

Referring to the drawings, in the particular embodiment of my invention therein shown, the heddle frame comprises top and bottom rails 5, connected at their ends by end members 6.

Each of the end members 6 comprises two separate strips 7 and 8, made of flat metal. The outer strips 7 extend over the ends of the top and bottom rails 5, and are bent over on the outer sides thereof, as at 9, being secured thereto by screws 10.

The inner strips 8 likewise have their end portions bent as at 11, extending along the inner sides of the top and bottom rails 5, and being secured thereto by screws 12.

The strips 7 and 8 of each end member 6 are permanently secured to each other, preferably by means of spot welding at various points 13 along the length thereof, whereby relative movement between the strips 7 and 8 will be eliminated, and the entire structure thus rendered quite rigid.

The heddle supporting bars 14, upon which

the heddles 15 are mounted, extend through slots 16 in the end members 6, and the portions of the heddle supporting bars 14 which project beyond the outer faces of the end members 6 are preferably apertured as at 17.

Each of the apertures 17 in the ends of the heddle supporting bars may be engaged by a hook-like extension 18 provided at the free end of a retaining device 19, which is preferably made of spring steel wire. The lower end of the device 19 extends through an aperture 20 in the outer strip 7 of the end member 6, then passing as at 21 within a slot 22 in the inner strip 8, again extending outwardly through an aperture 23 in the outer strip 7, and being bent over as at 24.

It will be noted that the portion 21 of the member 19 is located entirely within the slot 22 of the strip 8, so that no obstruction occurs on the inner face of the end member 6 which might cause the warp to foul during the reciprocation of the frames in the loom.

By the foregoing arrangement, there will be provided a heddle frame which will be relatively inexpensive to manufacture, light in weight, and at the same time will be quite rigid and durable.

Having thus described the nature and characteristic features of my invention, what I claim as new and desire to secure by Letters Patent, is:

A heddle frame comprising top and bottom rails, end members each comprising two separate flat metallic strips permanently united to each other at a plurality of points, one of said strips having its end portions extending across the ends of the top and bottom rails and bent over and secured on the outer sides thereof, the other of said strips having its end portions bent over and secured to the top and bottom rails along the inner sides thereof, heddle supporting bars extending through registered slots in the end members, and retaining devices comprising spring wire hook members each having its free end engaging one end of a heddle supporting bar and having its other end extending through apertures in the outer strip of each end mem-

ber, the portion thereof which is located on the inner side of said outer strip being positioned entirely within a slot in the inner strip of the end member.

⁵ In testimony whereof, I have hereunto signed my name.

JOHN JACOB KAUFMANN.
